[57] **CLAIM**

The ornamental design for a hermaphroditic electrical connector, as shown and described.

DESCRIPTION

FIG. 1 is a top plan view of one-half of an hermaphroditic electrical connector;

FIG. 2 is a side elevational view of the connector half shown in FIG. 1, the opposite side being a mirror image;

FIG. 3 is a bottom plan view of the connector half shown in FIG. 1;

FIG. 4 is a side elevational view of the other one-half of the hermaphroditic electrical connector which is arranged to mate with the connector half shown in FIG. 1, the opposite side being a mirror image;

FIG. 5 is an end view looking into the open end of the connector half shown in FIGS. 1 or 4;

FIG. 6 is an end view of the connector half of FIGS. 1 or 4, looking at the end opposite to that shown in FIG. 5; and,

FIG. 7 is side elevational view of the connector halves in an assembled condition.

The connector halves are shown separately in FIGS. 1-4 for clarity of illustration only.
